Primary Examiner — Sandra S Snapp*Assistant Examiner* — Ieisha N Price(74) *Attorney, Agent, or Firm* — Clark Hill PLC; James R. Foley(57) **CLAIM**

The ornamental design of a fastener, as shown and described.

DESCRIPTION

FIG. 1 is a perspective view of the fastener;

FIG. 2 is a front view of the fastener;

FIG. 3 is a back view of the fastener;

FIG. 4 is a left side view of the fastener;

FIG. 5 is a right side view of the fastener;

FIG. 6 is a top view of the fastener; and,

FIG. 7 is a bottom view of the fastener.

The broken lines in the drawings illustration portions of the fastener and form no part of the claimed design.

1 Claim, 6 Drawing Sheets(56)
